United States Patent Office

Des. 186,787
Patented Dec. 1, 1959

186,787

KNOB

La Verne E. Clayton, Rockford, Ill., assignor to Amerock Corporation, Rockford, Ill., a corporation of Illinois

Application August 1, 1958, Serial No. 52,016

Term of patent 14 years

(Cl. D50—3)

Fig. 1 is a front elevational view of a knob showing my new design.

Fig. 2 is a top view.

Fig. 3 is a side view of the knob.

Fig. 4 is a sectional view taken along the line 4—4 in Fig. 1.

Fig. 5 is a sectional view taken along the line 5—5 in Fig. 1.

Fig. 6 is a perspective view of the knob.

I claim:

The ornamental design for a knob, substantially as shown.
